(57) **CLAIM**

The ornamental design for a griddle plate, as shown and described.

DESCRIPTION

FIG. 1 is a top perspective view of a griddle plate, shown in environmental use, showing my new design;

FIG. 2 is a front elevation view thereof;

FIG. 3 is a bottom view thereof;

FIG. 4 is a top plan view thereof;

FIG. 5 is a rear elevation view thereof;

FIG. 6 is a left side elevation view, the right-side elevation view being a mirror image thereof;

FIG. 7 is a right-side sectional view taken along lines 7-7 from FIG. 2 thereof;

FIG. 8 is a bottom rear perspective view thereof; and,

FIG. 9 is a top rear perspective view thereof.

The broken lines in FIG. 1 are for the purpose of showing environment and form no part of the claimed design.

1 Claim, 6 Drawing Sheets
